UNITED STATES PATENT OFFICE.

JAMES L. McLAUGHLIN, OF NEW YORK, N. Y., ASSIGNOR TO SIDNEY GERNSBACK, OF NEW YORK, N. Y.

RADIO TUNING COIL.

Application filed June 29, 1922. Serial No. 571,806.

To all whom it may concern:

Be it known that I, JAMES L. McLAUGHLIN, a citizen of the United States, residing at 259 West 45th Street, in the county of New York and State of New York, have invented certain new and useful Improvements in Radio Tuning Coils; and I do hereby declare the following to be a full, clear, and exact description of the invention, such as will enable others skilled in the art to which it appertains to make and use the same.

This invention relates to radio transmission, or wireless communication and is directed more particularly to a tuning coil whereby the receiving and transmitting sets are synchronized or adjusted as to wave length.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application.

Figure 1 is a perspective view of a radio tuning coil embodying the invention.

Figure 2 is an elevation thereof, and

Figure 3 is a top plan view.

Corresponding and like parts are referred to in the following description and designated in the several views of the drawings by like reference characters.

The numeral 1 designates a hollow body of cylindrical form and constructed of insulating material such as pasteboard or fibre. A coil of wire 2 is mounted upon the body 1 and is subdivided into sections which are electrically connected by conductors 2^a with contacts 3 grouped about the body 1 and equally spaced from one another. One terminal of the coil 2 is grounded by means of a wire 4 and the other terminal is elec-

trically connected with a contact blade 5 attached to and carried by a rotary cap 6 fitted to an end of the body 1. While the contacts 3 may be of any construction, they are shown as consisting of ordinary paper fasteners, of which the contacts 3 are the heads and the shanks 3^a of which are passed through the body 1 and are clinched upon the inner side thereof. The contact blade 5 consists of a metal spring and is adapted to engage any one of the contacts 3 to bring any required portion of the coil 2 into action when tuning the set. The antenna 7 from the aerial connects with the contact blade 5. The detector as shown comprises the usual crystal 8 and fine wire or cat's whisker 9. The wires leading to the phones are designated by the numeral 10.

The tuning of the set is effected by rotating the member 6 on the body 1 until the desired results are attained. The frictional contact between the parts 1 and 6 is sufficient to hold the part 6 in the required adjusted position.

What is claimed is:

A tuning coil comprising a substantially cylindrical body member, a coil wrapped peripherally about the body member, a top member on said body member, one of said members being turnable with respect to the other member, contacts in insulated relation to the coil, said contacts having heads disposed exteriorly of the body member and in a row about the body member intermediate the coil and top member, a contact blade carried by said top member for coacting engagement with said heads, said contacts having securing shanks extending from the heads through and interiorly of the body member, and conductors leading from the coil secured to the shanks interiorly of the body member.

In testimony whereof I affix my signature in presence of two witnesses.

JAMES L. McLAUGHLIN.

Witnesses:

S. YENNERCOLT,
R. ACKERMAN.
